INVENTOR
ALFRED O. MARTIN

By A. O. Martin

UNITED STATES PATENT OFFICE

ALFRED OWEN MARTIN, OF RINGWOOD, ENGLAND

DOVETAIL-MARKER

Application filed December 3, 1929, Serial No. 411,344, and in Great Britain November 1, 1929.

This invention, which relates to dovetail markers, provides a marker characterized by two members so connected together as to be adjustable for scribing or marking dovetails of various sizes whose centre line lies at right angles, or lies obliquely to the face of the work.

In carrying out the invention, the marker is constituted by a fence and a plate with a 10 V-opening therein, the plate being movable not only longitudinally and at right angles to the fence, but also longitudinally and at angles other than a right angle to said fence, means being provided for locking the plate 15 and fence together when in adjusted position.

For a ready understanding of the invention, reference is to be had to the following description and accompanying sheet of drawings illustrative of a practical embodiment 20 of the invention, and wherein:—

Figure 1 is a plan view, the marker being set at right angles to the fence.

Figure 2 is a sectional view, taken on line 1—1 of said Figure 1.

Figure 3 is a plan view, the marker being set obliquely to the fence.

Like numerals of reference indicate corresponding parts in the several figures.

In carrying out the invention and referring to the drawings, the marker consists of 30 an oblong plate 2, and a fence constituted by two flat bars 3—3 between which the plate 2 is disposed, the said bars 3—3 being of greater length than the width of the plate 2, and 35 being connected together by means of bolts 4 and wing-nuts 5.

The plate 2, which engages and is slidable between the bars 3—3, is formed with a longitudinally disposed V-shaped fret or opening 6, the two long sides 7 of which are at an angle in relation to one another such as is usually used in the taper of dovetails, said sides 7 and the base 8 of said fret or opening 6 constituting marking or scribing edges 45 by means of which the dovetail may be scribed or marked on the work to be dovedtailed.

When scribing or marking dovetails whose centre lines lie at right angles to the side face 50 of the work in the edge of which the dove-

tails are to be formed, the bars 3—3 are moved together along the plate 2 and at right angles thereto, till the required size of dovetail is given by the sides 7—7 of the opening or fret 6, and the edges 9 of the fence 3—3, whereupon the wing-nuts 5 are tightened up to firmly clamp the plate 2 between the bars 3—3 of the fence.

The device is, by its fence 3, placed against the side face of the work aforementioned, 60 and a dovetail is scribed upon the edge of the work, and then the device is slid along the side face of the work to a required position for scribing another dovetail, and so on, thus enabling any number of dovetails to be 65 scribed or marked off by one setting of the device.

To scribe or mark dovetails whose centre line lies obliquely to the side face of the work in the edge of which the dovetails are to be 70 formed, the wing-nuts 5 of the fence 3—3 are slackened, and the fence 3—3 is moved over the plate 2 to the position or angle required, and also longitudinally along the plate 2 until the space between the edges 7—7 adjacent to the fence corresponds to required size of dovetail, as shown in Figure 3, whereupon the wing-nuts 5 are tightened up to clamp the plate, and the device then used in the manner above described to mark off any number of 75 dovetails with the one setting of the device.

I claim:—

1. A dovetail marker comprising a plate, a fence, the plate having elongated scribing edges forming between them an acute angle corresponding to the usual angle between the side faces of a dovetail formation, and means for securing the fence against the plate in different positions of adjustment along and in crossed angular relation to said scribing edges.

2. A dovetail marker comprising a plate having an elongated V-shaped opening therein in the side edges of which constitute marking edges and form therebetween an acute angle corresponding to the usual angle between the side faces of a dovetail formation, a fence, and means for securing the fence to the plate in different positions of adjustment along and in crossed relation to said opening.

3. A dovetail marker comprising a plate having elongated scribing edges forming between them an acute angle corresponding to the usual angle between the side faces of a dovetail formation, a fence comprising a pair of bars disposed against opposite faces of said plate, and screws connecting said bars for clamping them against said plate in different positions of adjustment along and in crossed relation to said scribing edges.

In testimony whereof I have affixed my signature hereto this ninth day of November, 1929.

ALFRED OWEN MARTIN.
